CLAIM

The ornamental design for a hand controller for video game, as shown and described.

DESCRIPTION

FIG. 1 is a perspective view of hand controller for video game showing our new design;

FIG. 2 is a front elevational view thereof;

FIG. 3 is a rear elevational view thereof;

FIG. 4 is a left top perspective view thereof;

FIG. 5 is a right top perspective view thereof; and,

FIG. 6 is a top plan view thereof.

FIGS. 2-5 are drawn in an enlarged scale and show only the upper shaft of the controller for clarity. The bottom is unornamented.
